UNITED STATES PATENT OFFICE

AUGUST F. HABENICHT, OF TINLEY PARK, ILLINOIS

CONTROL APPARATUS FOR AIR PRESSURE PUMP SYSTEMS

Application filed September 2, 1930. Serial No. 479,296.

This invention relates to control apparatus for air pressure pump systems.

The invention relates to subject-matter which is somewhat similar to that shown in my Patent No. 1,546,930, granted July 21, 1925, and embodies improvements over the structure shown therein.

A primary object of the invention is to provide apparatus of simple and staunch construction which will automatically deliver water from a well or container to a desired point. Another object is to provide mechanism by which water or other liquid may be lifted in a plurality of stages to a desired height. Other objects and advantages will appear as the specification proceeds.

The invention is fully described in the following specification and shown in the accompanying drawings, in which

Figure 1 is a part sectional view in elevation of apparatus embodying my invention; Fig. 2 is a detail view of a portion of the apparatus shown in Fig. 1; Fig. 3 is a top plan view; Fig. 4 is an enlarged sectional view of automatic locking apparatus, the section being taken as indicated at line 4 of Fig. 3; Fig. 5 is a part sectional view, the section being taken as indicated at line 5 of Fig. 6; Fig. 6 is an enlarged plan view of a portion of the apparatus, shown in Fig. 3; and Fig. 7 is a schematic view of the general plan or layout of the apparatus.

Referring more particularly to Fig. 7, A designates a tank of any suitable construction which is supported within a well or body of water. B designates a pump cylinder; C designates a faucet or discharge point; and D designates an expansion tank.

Tank A is provided with a check-valve 10 which permits the flow of water into the tank when the pressure within the tank is reduced but prevents the flow of water from the tank when compressed air is introduced thereinto. The tank is provided with a water draw-off pipe 11 which communicates with faucet C. Tank A is also connected with a compressed air line 12 which communicates at its other end with a valve chamber 13. Pipe 11 communicates with expansion tank D through

line 14, and with the pump chamber B through pipe 15.

The pipe line 11 is provided at a point between pipe 15 and the tank A with a check-valve 16 which is constructed so as to prevent back flow of water. On the opposite side of pipe 15, there is located in pipe 11 a spring-urged valve 17 which is set at a pressure of from, say, three to five pounds to prevent the flow of water toward the faucet C.

Referring now to Figs. 1 to 6, inclusive, the pump chamber B may be constructed in cylinder form and provided with a head 18 and a bottom 19. A freely movable piston 20 is mounted within chamber B and is formed preferably of a pair of metal plates 21 and a pair of cup-shaped leather disks 22 secured between the plates 20. Bolts or rivets 23 may be employed to secure the plates 21 and leather pieces 22 together.

Reciprocally guided through an opening in the bottom 19 is a plunger 24 which is pivotally secured at its outer end to a swing bar 25. The swing bar 25 is pivotally secured at one end to a fixed post 26. At its other end, the swing bar 25 has pivotal connections with a draw-bar 27 which extends to and is connected to lever 34. At an intermediate point bar 27 is provided with a shoulder 37. Above the shoulder 37, the bar 27 is reduced at 29. Telescopically received about the reduced portion 29 are the tubular members 28, 30, 31 and 33 which afford between them gaps or spaces for play 32. Lever 34 is pivoted at one end to a fixed post 35. At an intermediate point, the swing bar 34 is pivotally connected to a push rod 36. Located between the head 33^a with which bar 33 is provided and the shoulder 37 on rod 27, are two helical springs 38 which enclose the members 30, 31 and 33.

One of the springs 38 encloses members 28 and 30 and the other spring encloses members 31 and 33. Between the springs 38 and between members 30 and 31 is secured the end of a valve lever 39 which is also pivotally secured to post 35, bar 27 extending through the apertured end of lever 39.

The head 18 of the pump cylinder B is equipped with an exhaust valve seat 40 and an air inlet valve seat 41. Each of the

valves is provided with a box or casing which extends above the head. In the box above valve seat 40, apertures 42 are provided which allow the air within the pump cylinder to escape. A valve head is carried by a valve stem 43 which is reciprocally guided in the housing above the valve seat. The lower end of the valve head is secured to a hinged lever 44. The lever 44 also carries a valve stem 45 upon which a valve head adapted to seat in valve seat 41 is carried.

In the illustration given, a valve box 46 is supported adjacent the cylinder head 18 and is provided with an exhaust valve seat 47 similar to valve seat 40 with which cylinder B is provided. Above the valve seat 47 is a casing provided with exhaust ports 48. Reciprocally guided in the casing is a valve 49 which is connected to a hinged lever 50. The valve box 46 is also provided with an air valve seat 51 which is similar to valve seat 41 on the cylinder head 18. A valve is supported by a valve stem 52 which is connected to the hinged lever 50. Above valve seat 51 is a box or closed casing. An air line 53 which communicates with a compressed air tank (not shown) leads to the valve seat 41 of cylinder B, and the valve seat 51 of valve box 46. An air line 12 leads from valve box 46 to the well tank A.

An extension 54 of the valve bar 39 beyond post 35 is provided with a yoke 55 adapted to engage a spool head 56 with which the stem of valve 49 is provided. The swinging of lever 39 will thus serve to raise and lower valve head 49. Likewise the valve stem 43 is provided at its top with a stop member 57 adapted to engage the yoke 58 of a pivot bar 59. The yoke 58, as shown more clearly in Fig. 5, embraces valve stem 43. The pivot bar 59 is preferably pivotally secured to the short post 60 which is supported upon the head 18.

To actuate the pivot bar 59, weight mechanism is employed. As shown more clearly in Fig. 5, a weight 61 is suspended upon a shaft 62 which, in turn, is secured to a cross-piece 63. The cross-piece is provided at one end with a yoke 64 adapted to engage a guide member 65. At its other end, the cross-piece 63 is rigidly secured to a bar 66 which is reciprocally guided by a tube 67, the latter being secured by a member 68 to the head 18 of the pump cylinder B. The weight 61 is housed within a cylinder 69 which is provided near its bottom with two perforations 70 and 71 through which means for holding weight 61 in suspension may extend.

Referring more particularly to Figs. 2 and 3, the rod 66 is connected at its lower end to a flexible member 72 which, in turn, is connected to one end of a rock lever 73. The lever 73 is pivotally supported at 74. At its other end, the rock lever 73 is connected to

the long rod 75 which, in turn, is connected by means of a cross-piece 76 to the rod 33.

In order to secure quick action of the valves in seating and in opening, a bent rod 77 is connected to the bar 39 and near its lower end 70 is provided with a cam 78. The cam is supported adjacent a pin 79 and is drawn into contact with the pin by a horizontal spring 80.

Referring more particularly to Fig. 5, a latch member 81 is pivotally secured at 82 and carries at its lower end a pin 83 which is adapted to extend through opening 70 and to engage the bottom portion of weight 61. Connected to an intermediate portion of latch member 81 is a long pin 84 which extends across the path of the lever 39. When rod 39 is raised, therefore, it will engage the pin 84 and release the latch from engagement with weight 61.

Referring to Fig. 4, a second latch member 85 is pivotally supported at the point 86 and carries in its bottom portion a pin 87 which is adapted to extend through opening 71 and to engage the bottom of weight 61. 90 A spring-drawn rod 88 is connected to the lower portion of member 85 and tends to draw the latch member out of engagement with the weight. To hold the latch member in engagement with weight 61, a flexible diaphragm 89 carries a plunger 90 which bears against the member 85. The diaphragm 89 is supported within a chamber formed by casing 91 and the plunger 90 is guided within an opening provided by the casing. Communicating with the casing chamber on the side of the diaphragm opposite plunger 90 is an air line 92 which leads from the expansion tank D. The diaphragm 89, when the faucet C is closed, is normally held in the position shown in Fig. 4, the pressure of the air in the expansion tank D serving to press the diaphragm in a forward position.

In the operation of the apparatus, the operator opens faucet C. The moving parts are then in the position shown in Fig. 1. The opening of the faucet permits the air in expansion tank D to escape and thereby releases the pressure which has been urging diaphragm 89 toward a forward position. The plunger 90 is then retracted and the lever 85 is drawn back by spring-rod 88, together with the pin 87. The weight 61, being thus released, falls against one end of the rock lever 58. The yoke 58 is drawn against the stop member 57 and raises the valve against the valve seat 40. At the same time the valve lever 44 raises the valve out of valve seat 41, thus permitting compressed air to flow into the pump cylinder above the piston 20. Piston 20 is forced by the air downwardly and discharges the water contained in the cylinder through the pipe connection 15 and through the spring valve 17 to the faucet C. The check-valve 16 prevents 130

the flow of water back to the well. The piston 20 near the bottom of cylinder B strikes the rod 24 and causes lever 25 to swing downwardly drawing with it the long rod 27. Together with rod 27 is drawn the lever 34. The rod 75, which is connected to the member 76, an extension of member 34, is also drawn downwardly and depresses one end of rock lever 73. The opposite end of lever 73 is forced in an upwardly direction drawing, by means of the flexible connection 72, the rod 66 toward its raised position. Rod 66 raises with it the cross-piece 63 and the weight 61 suspended therefrom. As the weight is raised past the opening 70, the latch member 81, by reason of the weight of the long arm 84, swings inwardly bringing the pin 83 below the weight 61. The weight is thus held in suspended position.

As the long rod 27 is drawn down by the pressure of the piston 20 against rod 24, the lever 39 which is held between the members 30 and 31, is also depressed and the extension 54 of lever 39 is raised. During this operation the member 33 is drawn downwardly against the force of spring 38 and meets member 31, thereby depressing the lever 39. The yoke 55 of extension 54, being in engagement with the spool head 56 of the valve 49, raises valve 49 to close the exhaust ports. Lever 50 within the valve box 46 is also raised and the valve carried by rod 52 is lifted out of engagement with the valve seat 51. Compressed air now passes through line 53 into valve box 46 and out through line 12 to the tank A within the well or other body of water. This air forces the water within tank A through line 11 into the pump cylinder B. The check-valve 16 permits the flow of water in this direction, but the spring pressed valve 17, which is set at, say, from three to five pounds, prevents the flow of the water toward the faucet C. The inflow of water into the cylinder B raises the piston 20 to the top of the cylinder where it engages shaft 36. As shaft 36 is raised by contact with piston 20, the swing lever 34 is raised and the collar 37 on rod 27 lifts member 28 into contact with member 30, against the force of spring 28, thereby raising bar 39. The extension 54 of swing bar 39 presses down the valve 49 out of engagement with valve seat 47. At the same time, the swing bar 50 draws rod 52 down to seat the valve within valve seat 51. The supply of compressed air is thus cut off and the exhaust ports are opened. The air within the valve chamber 46 and also within the tank A in the well is exhausted through ports 48. Upon the removal of the compressed air from tank A, water flows through the check-valve 10 into tank A to fill it again.

As swing bar 39 is raised, it engages pin 84 and trips the latch member 81. If the faucet C remains open, so that the latch member 85 is inoperative, the retraction of the pin

84 will permit the weight 61 to fall striking the pivoted lever 59, and the cycle of operation which I have just described is repeated.

The rod 77 is retarded in its upward and downward movements by the engagement of cam 78 with pin 79. Also the telescopic members 33, 31, 30 and 28 cooperate with springs 38 and the rod 77 to permit a certain amount of play before the lever 39 is actuated. The operation of these parts serves to produce a quick closing and opening of the valves.

When faucet C is closed the apparatus continues to operate until piston 20 is in raised position, the cylinder B being substantially full of water. In this position, the lever 39 holds the latch member 81 out of contact with the weight. However, the weight 61 is maintained in elevated position by the latch member 85 which is pushed forward by plunger 90. Upon the closing of the faucet, the compressed air trapped in the expansion tank exerts a pressure on the flexible diaphragm 89 which forces plunger 90 toward a forward position. If the faucet C is opened, the operation, which has been described, is repeated.

It will be observed that the operation of the parts is automatic, and that the only movement required of the operator is that of opening and closing the faucet. The apparatus employed is sturdy and of simple construction, the use of needle valves and other delicate parts being avoided.

By employing a two-stage lift, the water may be discharged at the faucet with considerable pressure. While I have described an apparatus in which a two-stage lift is furnished, it is obvious that the parts may be multiplied to lift the water through a greater number of stages. In the final stage the water may be discharged substantially under the full pressure of the compressed air tank.

It will also be observed that with the form of apparatus illustrated, a supply of water is carried in the pump cylinder and is immediately available upon turning the faucet. It is not necessary for the operator to wait until water can be forced from the well to the faucet.

The foregoing detailed description has been given for clearness of understanding only and no unnecessary limitations should be understood therefrom, but the appended claims should be construed as broadly as permissible in view of the prior art.

I claim:

1. In apparatus of the character set forth, a compressed air supply, a tank within a body of water provided with a valve controlled inlet, a piston pump, automatic means actuated by said pump for supplying air from said compressed air supply to said tank, a water conduit from said tank to said cylinder, a discharge line communicating with said cylinder, and automatic means for controlling the flow of air from said supply to

the cylinder to force water through said discharge line.

2. In apparatus of the character set forth, a compressed air supply, a tank within a body of water provided with a valve controlled inlet, a pump cylinder communicating therewith, said cylinder being equipped with a slidable piston, automatic means actuated by said piston for supplying air from said compressed air supply to said tank, a water conduit from said tank to said cylinder, a discharge line communicating with said cylinder, and automatic means for controlling the flow of air from said supply to the cylinder to force water through said discharge line.

3. In apparatus of the character set forth, a compressed air supply, a pump casing, a slidable piston therein, means for supplying water to fill said casing, a discharge pipe communicating with said casing, and automatically controlled means associated with said piston for introducing compressed air into said pump when substantially filled to force the water into said discharge pipe.

4. In apparatus of the character set forth, a compressed air supply, a tank communicating with a body of water through a valve controlled inlet, a pump casing, a slidable piston therein, means for supplying water from said tank to said casing, a discharge pipe communicating with said casing, automatically controlled means associated with said piston for introducing compressed air from said supply into said casing when said casing is substantially filled, and valve means permitting the discharge of water through said discharge pipe.

5. In apparatus of the character set forth, a compressed air supply, a tank having a valved outlet communicating with a body of water standing above the bottom of said tank, a pump casing, a motor piston therein, a water conduit leading from said tank to said casing, a check-valve in said conduit permitting flow only toward said casing, a discharge pipe communicating with said casing, conduits leading from said compressed air supply to said casing and to said tank, and automatically controlled means associated with said air conduits and actuated by said motor piston for supplying compressed air successively to said tank and to said casing.

6. In apparatus of the character set forth, a compressed air supply, a tank having a valved outlet communicating with a body of water elevated above the bottom of said tank, a pump cylinder, a slidable piston in said cylinder, a water conduit leading from said tank to said cylinder, a check-valve in said conduit permitting flow only toward said cylinder, a discharge pipe communicating with said cylinder, conduits leading from said compressed air supply to said cylinder and to said tank, and automatically controlled means associated with said air conduits and

actuated by said piston for supplying compressed air successively to said tank and to said cylinder.

7. In apparatus of the character set forth, a compressed air supply, a tank having a valved outlet communicating with a body of water elevated above the bottom of said tank, a pump cylinder, slidable motor means therein, a water conduit leading from said tank to a discharge cock, a pipe connecting said conduit to said cylinder, a check-valve between said pipe and said tank, a spring-urged valve between said pipe and said cock, and automatic means actuated by said motor for supplying air from said compressed air supply to said tank and cylinder.

8. In apparatus of the character set forth, a compressed air supply, a tank having a valved outlet communicating with a body of water elevated above the bottom of said tank, a pump casing, a slidable piston therein, a water conduit leading from said tank to a discharge cock, a pipe connecting said conduit to said casing, a check-valve between said pipe and said tank, a spring-urged valve between said pipe and said cock, and automatic means controlled by said piston for supplying air from said compressed air supply to said tank and casing successively.

9. In apparatus of the character set forth, a closed pump cylinder, means for supplying liquid thereto, a piston slidably mounted in said cylinder, plungers slidably mounted at each end of said cylinder and extending thereto, fluid pressure inlet and outlet openings in said cylinder, valves controlling said openings, and means associated with said plungers for opening and closing said valves.

10. In apparatus of the character set forth, a compressed air supply, a closed cylinder, means for supplying liquid to said cylinder, a piston slidably mounted in said cylinder, a conduit leading from said compressed air supply to said cylinder, an exhaust pipe communicating with said cylinder, valves controlling said air inlet and said exhaust pipe, plungers slidably mounted in said cylinder and adapted to be actuated by said piston, a slidable weight member, means associated with said plungers for lifting said weight member, and a rocker-arm connected to said valves and adapted to be actuated by said weight member.

11. In apparatus of the character set forth, a compressed air supply, a closed cylinder, means for supplying liquid to said cylinder, a piston slidably mounted in said cylinder, a conduit leading from said compressed air supply to said cylinder, an exhaust pipe communicating with said cylinder, valves controlling said air inlet and said exhaust pipe, plungers slidably mounted in said cylinder and adapted to be actuated by said piston, a slidable weight member, means associated with said plungers for lifting said weight member.

member, a rocker-arm connected to said valve means and adapted to be actuated by said weight member, latch means for supporting said weight member in elevated position, and 5 automatic means for tripping said latch means to allow said weight to strike said rocker-arm.

12. In apparatus of the character set forth, a pump cylinder, a piston slidably mounted 10 in said cylinder, a plunger guided in the casting of said cylinder adapted to be actuated by said piston, a valve chamber provided with air inlet and outlet openings, valves controlling said openings, swinging lever means 15 adapted to actuate said valves, and yieldable means connecting said plunger member to said swinging lever.

13. In apparatus of the character set forth, a pump cylinder, a piston slidably mounted 20 in said cylinder, a plunger guided in the casting of said cylinder adapted to be actuated by said piston, a valve chamber provided with air inlet and outlet openings, valves controlling said openings, a swinging lever means 25 adapted to actuate said valves, yieldable means connecting said plunger member to said swinging lever, and means associated with said lever and yieldable means to effect the quick opening and closing of said valves.

30 14. In apparatus of the character set forth, a compressed air supply, a tank communicating through a valved pipe with a body of water elevated above the bottom of said tank, a conduit leading from said tank to a discharge cock, a pump cylinder communicating 35 with said conduit, a slideable piston in said cylinder, a valve permitting the flow of water from said tank to said cylinder but preventing back flow, a yieldable valve controlling the flow toward said cock, and automatic control means controlled by said piston for supplying air from said compressed air supply 40 to said tank and to said cylinder.

15. In apparatus of the character set forth, 45 a compressed air supply, a tank within a body of water provided with a valve controlled inlet, a hollow casing, a motor piston slidably guided therein, valve controlled means actuated by said motor for supplying air from 50 said compressed air supply to said tank, a water conduit from said tank to said casing, a discharge line communicating with said casing, and valve controlled means actuated by said motor for controlling the flow of air 55 from said supply to the casing to force air through said discharge line.

AUGUST F. HABENICHT.
